GUSTAF RENNERFELT, OF NEW YORK, N. Y., ASSIGNOR TO KOCHKUM, JR., & OHLSSON, OF NEW YORK, N. Y., A FIRM.

CENTRIFUGAL LIQUID-SEPARATOR.

SPECIFICATION forming part of Letters Patent No. 744,938, dated November 24, 1903.

Application filed January 13, 1903. Serial No. 138,938. (No model.)

To all whom it may concern:

Be it known that I, GUSTAF RENNERFELT, a subject of the King of Sweden and Norway, residing at New York, borough of Manhattan, 5 county and State of New York, have made a new and useful Invention in Centrifugal Liquid-Separators, of which the following is a specification.

My invention is directed especially to improvements in centrifugal liquid-separators; and it has for its object to so construct and arrange the operative parts of such a separator that the applied power for driving the same may be materially decreased, thereby 15 giving an increased capacity for a given amount of applied power.

My improvement, as illustrated in the accompanying drawings, represents a cream-separator.

20 Figure 1 is a sectional view taken through the body of the bowl of a centrifugal cream-separator in two planes at right angles to each other and illustrated by the section-lines Z Z, Fig. 2, and V V, Fig. 4. Fig. 2 is a trans- 25 verse sectional view taken through Fig. 1 on the line X X, and Fig. 3 is a similar trans- verse sectional view taken through Fig. 1 on the line Y Y. Fig. 4 is a plan view of the neck portion of the separator with the clamp- 30 ing-nut, which clamps the cover to the body of the bowl, removed.

Upon examining the construction of centrifugal liquid-separators now in general use one familiar with modern methods of machine 35 designing must be impressed by the peculiar fact that the direction of rotation of such machines and the size and number of the nozzles provided for the outflow of the skim-milk therefrom are immaterial to a certain extent.

40 High speed in cream-separators is an advantage, because it causes a more effective separation of the liquids and also because it gives a greater capacity to a machine of given size. The liquid to be discharged from the bowl 45 rotates, of course, with the same speed as the bowl, and when it escapes through a nozzle which is not wholly filled said liquid will have the same velocity as the peripheral speed of the nozzle and also in the same tangential 50 direction. This is due to the inertia of the liquid. The velocity of the liquid represents

energy which of course must be supplied by the driving power, and since this energy is proportional to the square of the velocity it is easily realized that with a fixed quantity 55 of liquid the speed necessary for good skimming will perhaps not be attained in many cases where the driving power is limited. With cream-separators the driving power is often limited, since most of them are designed 60 to be hand-driven.

With my improved machine I utilize hydrostatic pressure as the liquid issues from the nozzles in such manner that it will facilitate driving the bowl as it rotates. In other words, 65 I utilize this pressure in the same manner that it is utilized in driving turbines of the well-known reactive type and known generically under the name of the "Barker's mill" or "Tourniquet"—that is to say, I so locate the 70 skim-milk nozzles that they will discharge the liquid in a tangential direction opposite to the direction of the rotation of the bowl, and I further arrange them so that the velocity of the skim-milk in such tangential direction 75 will be as great as is practically possible. With such an arrangement when the milk is forced outward through the nozzles it will by its reactive action tend to drive the bowl in the same direction as that due to the applied 80 power and will therefore assist or aid said power. With my improvement I minimize the amount of energy required to drive the machine by reducing as far as is practically possible the velocity of the escaping skim- 85 milk in the direction of rotation of the bowl, and with this understanding of its operation it becomes a simple matter to calculate the actual saving in power which follows from the use of my improvement. 90

Referring now to the drawings in detail for a full and clear understanding of my invention, such as will enable others skilled in the art to construct and use the same, I represents the bowl, 2 the lid, 3 the neck of the lid, 95 and 4 the feeding-tube, 5 being the clamping-nut for securing the lid to the bowl, and 6 6 openings or holes from the feeding-tube to the interior of the bowl, all of the parts so far described being well known in the art. 100

m m are the skim-milk pipes, provided with enlarged cups *ff* at their inner ends and se-

cured to the inner and under side of the lid in any preferred manner.

5 *a a* are the nozzles, having their mouths *b* contracted, so that the quantity of the liquid which they are called upon to discharge cannot escape unless a certain velocity be imparted to the liquid. This velocity is derived from the hydrostatic pressure of the liquid contained in the nozzle between the entrance 10 *c* and the mouth *b*. The cups *f* are open at their inner ends, so that the pipes *m* may be readily cleansed by suitable brushes.

15 *d d* are overflow-openings at the upper edges of the cups *f*, their function being to take care of the overflow in the event of the machine being driven at abnormal speeds or the conditions of operation such that the nozzles *a a* will not carry away all of the skim-milk which is forced upward into the cups *f f*. These 20 openings *d d* are located somewhat nearer to the axis of rotation of the bowl than are the entrances *c c* to the nozzles *a a*, as is indicated by the cone-shaped form of the neck. It is necessary and well understood by those familiar with the art that the inner zone of the 25 skim-milk when the machine is in operation shall always be kept at a constant distance from the axis of rotation; otherwise the cream or lighter liquid forced out of the machine 30 will vary in thickness—that is to say, it will at different times contain a different amount of fat.

35 *h h* are cream-slots for the outflow of the cream, said slots being provided with the usual regulating-screws, as shown.

40 *g g* denote an edge in close proximity to the cream-slots *h h*, said edge being closer to the outer edges of the cream-slots than is usual in existing machines where the cream adheres 45 to the outer edge *k k* of the neck.

The operation is as follows: The regulating-screws having been set in the cream-slots *h h* to the desired points, as is customary in such machines, the milk to be treated is fed 50 continuously through the feeding-tube 4 and openings 6 6 to the bowl 1, and said bowl having been first set in rotation by the source of applied power (not shown) the denser milk passes outward and upward in the usual manner in the direction of the arrows through the pipes *m m* into the cups *f f*, thence outward through the entrances *c c* into the nozzles *a a*, filling said nozzles, so that the skim-milk contained therein, acted on by hydrostatic pressure, is caused to flow outward in a direction 55 the opposite of that of the rotation of the bowl, said direction being tangential. A diagrammatic illustration of this effect is found in Fig. 2 of the drawings, where the curved arrows indicate the direction of rotation of the bowl, the 60 arrows *p*, at the mouths *b b* of the nozzles, the velocity and direction of the flow of the milk due to hydrostatic pressure, and the arrows *r*, on the opposite sides thereof, the velocity 65 and direction in which the milk tends normally to flow in existing types of centrifugal separators with ordinary holes or openings,

the result being that the skim-milk leaves the nozzles with a velocity equal to the difference of these two velocities.

70 By reason of the inclined inner faces of the neck 3 and cups *f f* the escaping skim-milk will not ordinarily rise above the upper edges of the entrances *c c* of the nozzles *a a*; but should it do so, owing either to a decrease in 75 the speed of rotation or to an increase in the supply of liquid through the tube 4, the surplus skim-milk will pass through the openings *d d*, located closer to the center than the nozzles *a a*, the action in this particular being not different from the like action of well-known forms of centrifugal separators, the openings *d d* being, as above indicated, solely for the purpose of taking care of the overflow 80 from the cups *f f* when the machine is driven 85 too slowly or the supply of milk improperly increased.

It will be understood that the velocity of the cream upon leaving the bowl could by a similar nozzle also be minimized, as well as 90 the velocity of the skim-milk. The gain in power, however, would not be so great, since the amount of cream is so much smaller than the amount of skim-milk. The nozzle for the cream would also be correspondingly 95 smaller and more difficult to clean. In practice it may be preferable to let the cream escape in the ordinary manner. I, however, in such case provide the edge *g* in close proximity to the slot *h*, rather than to allow the 100 cream to adhere to the edge *k*, as is customary.

I do not limit my invention to the specific details of construction hereinbefore described, and illustrated in the accompanying drawings. I believe it is broadly new with me to 105 decrease the amount of applied power in a centrifugal separator by utilizing the outflow of the liquids to be separated, either or both, in such manner as to aid the applied power by reason of its reactive action as it leaves 110 the machine, and my claims are generic as to this particular.

I believe it is also broadly new with me to combine in a centrifugal liquid-separator nozzles so disposed that the outflow of the liquid 115 acts to aid in the propulsion of the machine, with overflow outlets or openings designed to take care of any excessive supply of the liquid either by reason of increased supply of the material to be acted upon or by decreased angular velocity given to the machine, and my 120 claims in this particular are designed to be of such scope as to include all equivalent devices for effecting such result.

Although I have illustrated my invention as 125 especially applicable to cream-separators, I do not limit it to such uses, as the same is of such scope that it may be used in connection with centrifugal liquid-separators generally, and my claims hereinafter made are designed 130 to include all such uses.

Having thus described my invention, what I claim, and desire to secure by Letters Patent of the United States, is—

1. A centrifugal liquid-separator having one or more nozzles carried by the bowl of the machine and tangentially arranged with relation to said bowl.
- 5 2. A centrifugal liquid-separator having one or more nozzles tangentially arranged with relation to the bowl of the machine and operatively connected with cups or chambers adapted to hold the liquid therein in such 10 manner as to utilize the hydrostatic pressure due to the rotation of the bowl.
- 15 3. A centrifugal liquid-separator having one or more nozzles carried by the bowl of the machine and tangentially arranged with relation to said bowl; in combination with one or more overflow-openings.
- 20 4. In a cream-separator a skim-milk escape consisting of a pipe open at both ends, the inner end of said pipe communicating with two 25 outlets one of which is adapted to be filled by the escaping skim-milk.
5. In a cream-separator a skim-milk escape consisting of a tube extending from near the periphery of the bowl toward the center thereof, the inner end of said tube being provided
- with two openings one of which is nearer to the axis of rotation of the bowl than the other.
6. In a liquid-separator an edge in close proximity to the escape for the lighter liquid for the purpose of minimizing the velocity of 30 said liquid when leaving the bowl.
7. In a centrifugal liquid-separator an outlet from the bowl, consisting of a contracted nozzle carried thereby and directed substantially tangentially opposite to the direction of 35 rotation of the bowl.
8. In a centrifugal liquid-separator an outlet from the bowl consisting of an overflow-opening; in combination with a contracted nozzle carried by the bowl and directed tangentially opposite to the direction of rotation 40 thereof.
- In testimony whereof I have signed my name to this specification in the presence of two subscribing witnesses.

GUSTAF RENNERFELT.
